SAMUEL W. AVIS, OF HARTFORD, CONNECTICUT, ASSIGNOR TO THE MERROW MACHINE COMPANY, OF HARTFORD, CONNECTICUT, A CORPORATION OF CONNECTICUT.

TAKE-UP FOR CROCHET MACHINES.

1,111,986.

Specification of Letters Patent. Patented Sept. 29, 1914.

Application filed January 9, 1913. Serial No. 741,052.

To all whom it may concern:

Be it known that I, SAMUEL W. AVIS, a citizen of the United States, residing at Hartford, county of Hartford, State of Connecticut, have made certain new and useful Improvements in Take-Ups for Crochet-Machines; and I do hereby declare the following to be a full, clear, and exact description of the same, reference being had 10 to the accompanying drawings, forming a part of this specification, and to the figures and letters of reference marked thereon:

This invention relates to that class of 15 crochet machines wherein a thread carrying implement passes the thread through the fabric and a hook or looper seizes this thread alternately above and below the fabric and draws it to the edge of the fabric, interlooping the thread to form an over-edge 20 crochet stitch or ornamental border; and the said improvements are adapted more especially for use in connection with machines of this class wherein provision is made for interlooping and incorporating in 25 the stitch or border additional or supplemental thread that does not penetrate the fabric.

One of the principal objects of my invention is to facilitate the formation of symmetrical and uniform stitches, another is to 30 facilitate altering the character of the stitch, and a further object is to pull off and take up thread for the stitch-forming 35 implements at the proper times and provide more perfect control of the thread than has heretofore been possible.

Other objects will hereinafter become apparent.

My invention is an improvement on the 40 device set forth in an application Serial No. 741,060, filed by Joseph M. Merrow January 9, 1913, and consists of certain new and useful features, combinations and details of construction hereinafter described 45 and claimed.

Referring to the accompanying drawings:—Figure 1 is a front elevation of a 50 crochet machine containing an embodiment of my invention. Fig. 2 is a left end elevation of the embodiment of my invention shown in Fig. 1 and of the adjacent parts of the machine. Fig. 3 is a front elevation of Fig. 2 with the moving parts in another position, and having parts removed and 55 part of the frame being broken away to

show the disposition of the threads and the positions of the stitch forming implements more clearly. Fig. 4 is a plan view of the elements of my improvement and adjacent parts of the machine taken from the line 4—4 of Fig. 3, some of the parts of the machine being shown in section.

The particular embodiment of my device shown in the drawings is a form particularly suitable for use on both plain and shell stitch two thread crochet machines of the well known Merrow type.

Examples of plain crochet machines are set forth and referred to in United States Patents #414,718, issued November 12, 1889 and 497,587, issued May 16, 1893. In the shell stitch machines the fabric is fed only after several stitches have been formed at or near one point. The stitches are thus formed in clusters and when the fabric is fed along they are spread out at their outer extremity and assume a form similar to that of a fan or of a scallop shell. The production of stitches of this nature is set forth in United States Patents #414,233 and 414,235, both issued November 5, 1889; and machines for producing shell stitches are shown in 448,722, issued March 24, 1891; and 1,045,163, issued November 26, 1912.

For the purpose of illustration, a preferred embodiment of my invention has been shown applied to a Merrow shell stitch machine wherein:—

1 indicates the needle, 2 the needle bar, 3 the link connecting the needle bar clamp 4 to the needle bar lever 5 by means of the screw studs 6 and 7; the oscillating reciprocating crochet hook 8 has a latch 8^a and is operated in the usual manner. The supplemental thread carrier 9 vibrates in a path that is at an angle both to the axis of the needle bar and to the path of the hook, and it is adjustably secured to the rock shaft 10.

The numeral 13 indicates the chaining finger, 14 the needle plate, 15 the work plate, 16 the fabric being finished, 17 the machine frame and 17^a the frame head.

The elements 17^b and 17^c are bosses on the frame head, 18 is the needle thread tension, 19 is the supplemental thread tension, 20 is a needle thread guide and 21 a supplemental thread guide.

In the operation of machines as thus far described, as the needle ascends and its eye

emerges from the upper surface of the cloth, it draws the needle thread out of the straight line between the guide eye 20 and the point where the thread penetrates the fabric, and thus draws a slight supply of thread and, as the needle descends the needle eye reversing its action lets out this supply of thread to the crochet hook. The supplemental thread carrier vibrating between the guide 21 and the edge of the fabric so as to cross the paths of the needle and the hook, serves to pull off from the tension and deliver to the hook some of the supplemental thread used in making the 10 stitch. In the operation of such machines in certain classes of work, it frequently occurs that there is undue strain imposed upon the thread during portions of the 15 stitch-forming cycle, causing irregularity of stitching, breaking of thread and other imperfections in the operation of the machine. It is the particular purpose of this 20 invention to reduce and eliminate these and other undesirable tendencies, and further, to control the conditions in the stitches and 25 the character of the finish.

In the improvement as illustrated, 22 is a reciprocating take up eye having thread 30 passages or eyes 22^a and 22^b in its head and a shank portion 22^c which is secured to the stud 7 by means of the set screw 23. The head or body portion of the screw stud is made somewhat longer than usual so that the set screw 23 may be readily accessible. Being secured to a stud that is 35 in fixed relation with the needle bar, the eye 22 is reciprocated, ascending and descending with the ascent and descent of the needle. The three take-up thread arms 40 24, 25 and 26, having the thread passages or eyes 24^a, 25^a and 26^a respectively, are secured to the frame head 17^a by the screws 27, 28 and 29, upon which the arms may 45 be swung to adjust the position of the eye thereon.

The needle thread as it comes from the tension 18, is preferably threaded through the outer thread passage 22^a in the eye 22, then through the eye 26^a of the arm 26, and 50 then through the guide 20 to the needle eye. The supplemental thread as it leaves the tension 19 is threaded through the passage 24^a in the arm 24, then through the passage 22^b of the eye 22, then through the passage 55 25^a of the arm 25, and finally through the guide 21 to the supplemental thread carrier 9. The needle thread is made to appear somewhat darker than the supplemental thread throughout the drawings for the 60 sake of clearness. The eye 22^a in descending, bends or pulls the needle thread out of the straight line between the tension 18 and the eye 26^a, thereby pulling needle thread through the tension, and the eye 22^a 65 in rising, slackens this thread by permit-

ting it to again approach the straight line between the tension and the eye 26^a. The eye 22^b, in descending from the top of the stroke about as shown in Fig. 1, slackens the supplemental thread as it approaches the position shown in the dotted lines in Fig. 3 by decreasing the distance between the moving eye 22^b and the two fixed eyes 24^a and 25^a, through which the supplemental thread passes. Then passing 75 this position and continuing on to the bottom of its stroke, the eye 22^b pulls off thread by increasing the distance between the moving eye 22^b and the two fixed eyes 24^a and 25^a. The ascending of the 80 eye 22^b slackens the supplemental thread as it approaches a position midway between the two eyes 24^a and 25^a and, passing this position in its continued ascent the eye 22^b takes up a more or less definite amount of 85 the slack in the supplemental thread according to the adjustment of one or both of the two fixed eyes. The supplemental thread and needle thread take-ups, coöperate with the supplemental thread carrier, the needle 90 and the crochet hook to ease up or slacken the thread at suitable periods, and also to take up the threads and to pull the threads through the tensions at suitable times. The amount of thread pulled off can be regulated within practical limits by changing the positions of the thread eyes 24^a 25^a and 95 26^a, thus making the loops of the finish tighter or looser as may be desired.

Having thus described my invention, I 100 claim,

1. A take up for plural thread machines embodying a reciprocating implement, two pairs of stationary thread supporting elements coöperating with the said implement, 105 one pair being arranged at one side of and in a line substantially parallel with the path of the implement and the other pair being arranged one on either side of and in a line inclined to the path of the implement. 110

2. In a two thread crochet machine including a needle, a needle bar and mechanism for actuating the same, the combination of a plurality of thread supporting elements mounted one above the other on a stationary portion of the machine and at one side of a line parallel with the needle bar, a thread supporting element for one of the threads on the opposite side of said line, 115 a take up implement carried by a member of the needle bar actuating mechanism in a path parallel with the needle bar, and operating upon both of the threads each between two independent points of support, 120 to pull off and control each of the threads independently of the other. 125

3. A thread controlling system comprising a reciprocating thread carrying implement and two pairs of stationary thread 130

supporting elements with which the said thread carrying implement coöperates, one pair being arranged on one side of the path of reciprocation of the implement and the other pair being arranged one on each side of the path of the implement and in a line diagonal thereto, means whereby the distance between the respective elements of each pair of thread supporting elements may be adjusted, a support for the said thread supporting elements and means for carrying and actuating the thread carrying implement.

4. In a two thread crochet machine including a needle bar and mechanism for actuating the same, a thread pull off and take up embodying three thread guides mounted on a stationary portion of the machine at one side of a line parallel with the needle bar and in the direction of its reciprocation with relation to each other, a tension mounted at the side of said line opposite to that on which the thread guides are located, a thread eye carried by the needle bar mechanism and reciprocating between the tension and the thread guides, and means for adjusting the thread guides relatively to each other and with relation to the tension, in the direction of the reciprocation of the thread eye.

5. In a two thread crochet machine, a take up for the two threads embodying two pairs of thread supporting elements, a reciprocating thread engaging implement, the thread supporting elements being arranged one pair at one side of the path of the reciprocating implement and the other pair

one on each side of the path of the implement and in a line diagonal to said path, the threads being passed through the reciprocating thread engaging implement intermediate the elements of the respective pairs of thread supporting elements, whereby one thread is constrained at two points on the same side of the path of the implement and the other thread is constrained at two points on opposite sides respectively of the said path and in a line diagonal thereto, while the thread intermediate the points of constraint is reciprocated in the path of the implement.

6. In a crochet machine adapted to forming overedge stitches from a main thread carried by an eye pointed needle and a supplemental thread interlooped with the main thread by means of a crochet hook, the combination of take up devices for the main and supplemental threads, the said devices including a moving implement and two pairs of thread supports, one pair coöperating with the implement for each thread, the path of movement of the implement being between the elements of the pair of main thread supports and at one side of the line of the elements of the pair of supplemental thread supports whereby the main and supplemental threads are pulled off and controlled substantially as shown and described.
